(54) **SPINNING, FLIERS, COTTON**

(76) Inventor: **John Morse**

1801. - Merle of Newbury, - Massachusetts.

Letters Patent.

The schedule referred to in these Letters Patent and making part of the same containing a description in the words of the said Sager himself of his improvement in the mode of constructing or making fliers for spinning Cotton, wool, silk, flax and hemp."

To all to whom these presents shall come,

Be it known that Sager a citizen of Newbury in the County of Hiddberg and Commonwealth of Massachusetts a blacksmith both invented a new and useful improvement in the mode of constructing and making fliers for spinning of Cotton, wool, silk, flax or hemp, and connecting therewith when it is desirable to have such a connection, and in such case making part of said fliers a wheel for the purpose of driving the same and that the following is a full and exact description of the construction and use of said improvement as invented by him,

My said invention consists in constructing making and finishing said fliers and with or without Whees as their uses may require of one entire piece, and to accomplish this object, I cause the fliers alone or the fliers and wheel when used in connection and of any size or form or size to be cast entire in moulds, and of a malleable iron or steel so that they may be wrought, on the rough and finished as the operating mechanism may desire and so as to adapt them to all uses for which the common fliers as now usually constructed are applied.

The great practical benefit arising from the use of fliers, constructed in this mode invented by me is - that the fliers being of one entire piece, and being well and sufficiently tempered is stiff and durable having no connecting joints as in the common flier, which is constructed of four or more pieces connected together by braging or otherwise, and its weight acting when applied to use, frequently causes the part to work loose,

... and "Whatever may be introduced or mentioned on the foregoing specification my whole invention consists in the invention whereby - fliers alone or others with wheels may be cast in one entire piece, and finished from said casting

I say no claim to the Invention of a flattable iron or steel or to any other material used for their construction,

The model transmitted number 1, exhibits one of my floors... cast and finished from the rough cast material; 2, exhibits a floor with the webs connected... being one entire piece of casting...

In testimony that the above is a true specification of my said invention as above described, I have hereunto set my hand this twenty eighth day of September in the year of our Lord one thousand eight hundred and thirty five.

Witness,

Thomas A. Dugler
J. J. Avery Davis
